VARIABLE SPEED REDUCER

Howard E. Morris, Chicago, Ill.

Application May 16, 1956, Serial No. 585,215

10 Claims. (Cl. 74—342)

My invention relates generally to a variable speed reducer and more particularly to a novel gear train arrangement for use in a variable speed reducer.

The popular trend of employing miniature battery powered electric motors in mechanical toys has presented a problem of providing economical means for reducing the speed of the motor to a desired rate without, of course, resorting to the use of rheostats or the like in the motor circuit. Such motors are mass produced at relatively low cost and usually operate at speeds of 4000-5000 r.p.m. It is of course understood that speed requirements in different types of toys may vary requiring in each case, a different gear train arrangement. This necessitates special consideration for each different application with a special gear train arrangement for each case. Thus, while the motor may be mass produced in large quantities and the same type of motor may be employed in a great many types of toys the same has not been true of the gear train arrangements heretofore used, each of such arrangements requiring individual tooling and different fabrication with a consequent higher cost of production.

Accordingly it is an object of my invention to provide a speed reducer adapted for attachment to a motor housing and embodying a novel gear train arrangement utilizing identical interchangeable gears which may be arranged in operative engagement according to a predetermined order to provide a series of speed reductions of different values within a certain range.

Another object of my invention is the provision of a device of the foregoing character which may be economically mass produced and in which a single basic structure may be employed in a great variety of applications, it being required only to utilize one or more of a series of interchangeable gears with such structure to obtain a desired reduction in speed.

A further object of my invention is the provision of a device of the foregoing character which lends itself to fabrication by moulding from plastic materials or by die casting.

Other and further objects and advantages of my invention will become apparent when considered in connection with the following description and the accompanying drawing in which

Fig. 1 is a vertical cross sectional view illustrating an embodiment of my invention.

Fig. 2 is an elevational view taken on line 2—2 of Fig. 1 with the cover removed.

Fig. 3 is a more or less diagrammatic view showing the gear train arrangement illustrated in Fig. 2.

Fig. 4 is a perspective view partly in cross section of the body structure showing the relationship of the gear supporting studs.

Fig. 5 is a view similar to Fig. 4 and showing the gear train supported on the studs.

Figs 6 and 7 are respectively front and side elevational views of an interchangeable gear.

Fig. 8 is a view taken on line 8—8 of Fig. 1, and

2

Fig. 9 is a view taken on line 9—9 of Fig. 1.

Referring to the drawings the numeral 15 indicates generally an electric motor which except for certain structural features incorporated in the end housing member 16 as will be presently described is of conventional construction. The said end housing member 16 includes the usual axial bearing in which is journaled one end of the armature shaft 18 on which is fixed a driving pinion 19 exteriorly of end housing member 16. The opposite end of shaft 18 is journaled in the opposite end housing 17. The said end housing member 16 is provided with a series of rectangular apertures 21 spacedly arranged and adapted to receive cooperating hook elements 22 attached to a speed reducer assembly 23, the said hook elements serving to secure said assembly to the motor housing.

The speed reducer assembly 23 comprises a generally cylindrical housing 24 having a circular transverse wall 26 and a skirt portion 27 eccentric to the housing 24, as seen clearly in Fig. 8. Extending rearwardly from the wall 26 are a plurality of fingers 28 each having at its end a hook element 22 adapted to engage against a respective embossed portion 29 adjacent each of the apertures 21 in the end housing member 16. When the parts 25 are assembled the fingers 28 are caused to flex outwardly in passing through the apertures 21. When the hook elements 22 are passed completely through the apertures the fingers 28 assume the position illustrated in Fig. 1 with the skirt portion 27 engaging against an annular seat 31 in the end housing member 16. The parts thus are held securely in assembled relation.

As seen clearly in Figs. 1 and 8 the transverse wall 26 within the area circumscribed by the skirt portion 27 is offset to provide a circular well (Fig. 4) with a portion of the wall 26a cut away to provide a clearance opening 33 in which is received a portion of the driving pinion 19. A post 34 extends from the center of the well 32, the post having a base portion 35 of increased diameter to afford a thrust bearing surface for the first gear element 36 rotatably supported on the post 34. Said first gear element 36 includes a relatively thin spur gear 37 adapted to operatively engage with the pinion 19 and an integral spur gear 38 of substantially increased axial length. The gear 38 extends beyond the surface of the wall 26 as seen clearly in Figs. 1 and 5.

Disposed centrally of the wall 26 is a hollow boss 39 affording a bearing for rotatably supporting an outlet shaft. Circumferentially spaced on a circle, the radius of which is equal to the distance between the axis of boss 39 and the axis of post 34 are a plurality of posts 42, 43, 44, 45, 46, 47 and 48. Each of the said posts includes a lower portion which has a diameter greater than the upper portion to afford a thrust bearing surface for supporting a gear element 51 (Figs. 6 and 7) adapted to be rotatably carried on the upper post portion and hereinafter to be described.

Referring particularly to Fig. 4 it will be seen that the lower enlarged portions of the posts 42-48 are of different heights with the post 42 immediately adjacent the post 34 being the shortest and the remaining posts in a counterclockwise direction increasing progressively in height in the manner of a helix with the post 48 having the greatest height. Each of these posts is adapted to rotatably support a gear element 51 illustrated in detail in Figs. 6 and 7. All gear elements 51 are identical and may be molded as a unit to include two integral spur gears 52 and 53 each having different numbers of teeth. For convenience the respective gear elements and components thereof will be identified by suffixes *a*, *b*, *c*, *d*, *e*, *f* and *g*. For example, gear 52 in the present embodiment has 8 teeth while gear 53 has 12 teeth. The enlarged portions of the respective posts are so arranged that coop-

erating gears of successive gear elements operate in progressively higher planes with the smaller gear of one gear element being in operative engagement with the larger gear of a succeeding gear element. For example gear 52a on post 42 is adapted to be operatively engaged with gear 53b on post 43, the said gears 52a and 53b being disposed substantially in the same plane. Gear 52b on post 43 correspondingly is adapted to be operatively engaged with gear 53c on post 44, the said last mentioned gears similarly being in the same plane. The same relationship holds true for each of the cooperating succeeding gear elements. It will be apparent that in each step through the train of gears a reduction in speed is effected.

Mounted on the output shaft 41 for rotation therewith is a gear 54. As will be seen by reference to Fig. 2 the said gear has a greater number of teeth than any of the gears 52 with which the gear 54 is adapted to cooperate in the embodiment illustrated the gear 54 has 18 teeth. As viewed in Fig. 3 the pitch diameter of gear 54 is tangent to the projected pitch diameter of each of the respective gears 52 such that if the gear 54 were shifted axially into planar alinement respectively with each of the gears 52 and gear 38 each of said gears would be separately operatively engaged with gear 54.

Where a maximum gear reduction is desired a full complement of gear elements 51 will be employed as illustrated in Figs. 2, 3 and 5. Under such conditions utilizing all the gears illustrated there is obtained a speed reduction ratio of 1:013 between the motor shaft 18 and the output shaft 41. In the last described condition the gear 54 is disposed in planar alinement and in operative engagement with gear 52g supported on post 48. If a lesser speed reduction ratio is desired for example 1:019 the gear element 51g on post 48 is eliminated and the gear 54 is positioned on shaft 41 so that it will be in planar alinement and in operative engagement with gear 52f on post 47. It will be understood that it is contemplated to provide shaft 41 with longitudinal splines and press fit the gear 54 thereon at the desired axial position so that it is disposed in planar alinement with a particular gear 52. Thus, by placing the gear 54 at different longitudinal positions on the shaft 41 the said gear may be caused to cooperate with different gears 52 to provide different speed reductions, it being understood that all gear elements 51 following in a counterclockwise direction, as viewed in Fig. 2, the gear element meshed with the gear 54 will be eliminated, since such gear elements do not function. For example, utilizing the gear train combinations below indicate the following gear reduction ratios between the motor shaft 18 and the output shaft 41 may be obtained.

Gear train combination:	Gear reduction ratio
Gears 38 and 54	1:222
Gears 38, 53a, 52a and 54	1:148
Gears 38, 53a, 52a, 53b, 52b and 54	1:098
Gears 38, 53a, 52a, 53b, 52b, 53c, 52c and 54	1:066
Gears 38, 53a, 52a, 53b, 52b, 53c, 52c, 53d, 52d and 54	1:044
Gears 38, 53a, 52a, 53b, 52b, 53c, 52c, 53d, 52d, 53e, 52e and 54	1:029
Gears 38, 53a, 52a, 53b, 52b, 53c, 52c, 53d, 52d, 53e, 52e, 53f, 52f and 54	1:019
Gears 38, 53a, 52a, 53b, 52b, 53c, 52c, 53d, 52d, 53e, 52e, 53f, 52f, 53g, 52g and 54	1:013

A cap member 56 having central aperture to journal shaft 41 is provided with an annular undercut flange 57 and affords a closure for the housing 24 which has a cooperative flange 58, the two flanges being adapted to snap into interlocking engagement when the parts are assembled. Formed integrally with the inner face of the cap member is a plurality of bosses 59, 60, 61, 62, 63, 64, 65 and 66. These bosses are of varying lengths and are arranged in a circle coaxially with corresponding posts 34, 42, 43, 44, 45, 46, 47 and 48 respectively. Each of the bosses is provided at its end position with a bore

in which is received the corresponding end of a respective post. The end of said bosses each afford a thrust bearing surface for a respective gear element to maintain the same assembled relation. It will be understood that the lengths of said bosses are complementary to those of the posts such that the shortest post will have cooperating therewith the longest boss and vice versa.

It will be apparent from the foregoing that my invention affords an economical and highly versatile and efficient arrangement for providing a variety of speed reduction ratios with a common basic structure, it being merely required to utilize one or more of a series of identical interchangeable gear elements with said basic structure to obtain a desired speed reduction within the range of the device.

It will be understood that various changes and modifications may be made from the foregoing without departing from the spirit and scope of the appended claims.

I claim:

20 1. A device of the character described comprising an input shaft having a gear mounted thereon, an output shaft, a gear mounted on said output shaft, a series of similar rotatably mounted gear elements spacedly arranged in a helix coaxial with the output shaft, each of said gear elements consisting of two gears one having a greater number of teeth than the other and a gear of one gear element being adapted to mesh with a non-corresponding gear of an adjacent element, the pitch diameters of corresponding gears of said series of elements being equal and all projected pitch diameters being tangent to the pitch diameter of said output gear, said input shaft gear being in operative engagement with one of said series of gear elements, said output gear being adapted to be selectively positioned axially of said output shaft for selective cooperative engagement with one of said corresponding gears for varying the speed reduction ratio between said input and said output shafts.

25 2. A device of the character described comprising a base, an output shaft rotatably supported in said base, a plurality of posts supported on said base and spacedly arranged radially equidistant from the axis of said output shaft, a gear supported on said output shaft, a plurality of similar gear elements, one rotatably supported on each of said posts, each gear element comprising two gears in juxtaposition with one of said gears having a greater number of teeth than the other of said gears and with non-corresponding gears of adjacent gear elements being in operative engagement, the projected pitch diameters of all of the gears of one series of corresponding gears being equal and tangent to the pitch diameter of said shaft gear, said last mentioned gear being adapted to be selectively positioned axially of said shaft for selectively cooperative engagement with one of the gears of said one series for varying the speed between said input and output shafts.

30 3. In a device of the character described, an output shaft, a gear carried on said shaft, an input shaft, a gear carried on said shaft, a series of posts spacedly arranged radially equi-distant from the axis of said output shaft, a first series of identical gears, each rotatably supported on a post, a second series of gears each rotatably supported on a post, a gear of said first series being in operative engagement with an adjacent gear of said second series, the gears on each of said posts being operatively connected, the projected pitch diameters of all of the gears in said first series being equal and tangent to the pitch diameter of said output shaft gear, said last mentioned gear being adapted to be selectively positioned axially of said shaft for selective cooperative engagement with one of the gears of said first series for varying the speed between said input and said output shafts.

35 4. In a device of the character described comprising an input shaft having a gear thereon, an output shaft having a gear thereon, a train of similar rotatably supported gear elements, each of said gear elements consisting of two gears with one of said gears having a larger number of

teeth than the other and arranged in cooperative engagement so that the gear with the smaller number of teeth will cooperatively engage an adjacent gear of a larger number of teeth, said output gear adapted to be selectively positioned axially of said output shaft for cooperative engagement with any one of the gears having the smaller number of teeth for varying the speed ratio between said input and said output shafts.

5. In a device of the character described comprising an input shaft having a gear thereon, an output shaft having a gear thereon, a train of similar rotatably supported gear elements operated by said input gear, each of said gear elements consisting of two gears with one of said gears having a larger number of teeth than the other gear, said gear elements being arranged in progressively higher planes with the small gear of one gear element in operative engagement with the larger gear of a succeeding gear element, said output gear adapted to be selectively positioned axially of said output shaft in planar alinement with any one of the gears having the smaller number of teeth for cooperative engagement therewith for varying the ratio between said input and said output shafts.

6. In a device of the character described comprising a housing having a plurality of posts of progressively increasing heights, a gear element rotatably supported on each of said posts, each said gear element consisting of two gears with one of said gears having a larger number of teeth than the other gear, said gear elements being arranged in progressively higher planes on said posts with the gear with the smaller number of teeth of one gear element in operative engagement with the gear having a larger number of teeth of a succeeding gear element, an input gear for operating said chain of gear elements, an output gear mounted on an output shaft and operated by said chain of gear elements, said output gear adapted to be selectively positioned axially of said output shaft in planar alinement with any one of the gears having the smaller number of teeth for cooperative engagement therewith for varying the ratio between said input and said output shafts.

7. In a device of the character described comprising a housing having a plurality of posts of progressively increasing heights, a gear element rotatably supported on each of said posts, each said gear element consisting of two gears with one of said gears having a larger number of teeth than the other gear, said gear elements being arranged in progressively higher planes on said posts with the gear with the smaller number of teeth of one gear element in operative engagement with the gear having a larger number of teeth of a succeeding gear element, an input gear for operating said chain of gear elements, an output gear mounted on an output shaft and operated by said chain of gear elements, said output gear adapted to be selectively positioned axially of said output shaft in planar alinement with any one of the gears having the smaller number of teeth for cooperative engagement therewith for varying the ratio between said input and said output shaft, a closure member for said housing having bosses of varying lengths with bores for receiving said posts, the ends of said bosses affording a thrust bearing for said gear elements.

8. In a device of the character described comprising a housing having a plurality of posts provided with thrust bearings of progressively increasing heights, a gear element rotatably supported on said post adjacent said thrust bearing so that said gear elements are arranged in progressively higher planes, each said gear element consist-

ing of two gears with one of said gears having a larger number of teeth than the other gear and the gear with the smaller number of teeth in operative engagement with the gear having a larger number of teeth of a succeeding gear element, an input gear for operating said gear elements, an output gear mounted on an output shaft and operated by said gear elements, said output gear adapted to be selectively positioned axially of said output shaft in planar alinement with any one of the gears having the smaller number of teeth for operative engagement therewith for varying the ratio between said input and said output gears.

9. In a device of the character described comprising a housing having a plurality of posts provided with thrust bearings of progressively increasing heights, a gear element rotatably supported on said post adjacent said thrust bearing so that said gear elements are arranged in progressively higher planes, each said gear element consisting of two gears with one of said gears having a larger number of teeth than the other gear and the gear with the smaller number of teeth in operative engagement with the gear having a larger number of teeth of a succeeding gear element, an input gear for operating said gear elements, an output gear mounted on an output shaft and operated by said gear elements, said output gear adapted to be selectively positioned axially of said output shaft in planar alinement with any one of the gears having the smaller number of teeth for operative engagement therewith for varying the ratio between said input and said output gears, and an end closure member for said housing having thrust bearings of progressively varying heights in inverse order to the thrust bearings of said posts, said last mentioned thrust bearings supporting said gear elements against removal.

10. In a device of the character described comprising a housing having a plurality of posts provided with thrust bearings of progressively increasing heights, a selective number of gear elements mounted on certain of said posts dependent upon the gear reduction desired, said gear elements rotatably supported on said posts adjacent said thrust bearings so that said gear elements are arranged in progressively higher planes, each said gear element consisting of two gears with one of said gears having a larger number of teeth than the other gear and the gear with the smaller number of teeth in operative engagement with the gear having a larger number of teeth of a succeeding gear element, an input gear for operating said gear elements, an output shaft, an output gear mounted on said output shaft, said output gear adapted to be selectively positioned axially of said output shaft in planar alinement with the highest positioned gear having the smallest number of teeth for operative engagement therewith for varying the ratio between said input and output gears.
